UNITED STATES PATENT OFFICE

158,869

DUMMY BOOK OR SIMILAR ARTICLE

Richard Kent, New York, N. Y.

Application June 24, 1949, Serial No. 3,523

Term of patent 7 years

(Cl. D6—2)

To all whom it may concern:

Be it known that I, Richard Kent, a citizen of the United States, residing in the city, county, and State of New York, have invented a new, original, and ornamental Design for a Dummy Book or Similar Article, of which the following is a specification, reference being had to the accompanying drawings forming part hereof.

Fig. 1 is a side elevational view of the dummy book or similar article, showing my new design, the opposite side presenting substantially the same appearance as the side shown.

Fig. 2 is a back view thereof.

Fig. 3 is an end view of the same.

I claim:

The ornamental design for a dummy book or similar article, as shown and described.

RICHARD KENT.
